UNITED STATES PATENT OFFICE.

EDWARD A. PRIDMORE, OF CHICAGO, ILLINOIS.

MOLDING-MACHINE.

1,102,606.

Specification of Letters Patent.

Patented July 7, 1914.

Application filed October 26, 1912. Serial No. 727,857.

To all whom it may concern:

Be it known that I, EDWARD A. PRIDMORE, a citizen of the United States, residing at Chicago, in the county of Cook and State 5 of Illinois, have invented a new and useful Improvement in Molding-Machines, of which the following is a specification.

My invention relates, more particularly, to flask-receiving and supporting means 10 commonly provided in molding machines for receiving the rammed flask and supporting the same in the pattern-drawing operation, my present invention, having been devised for use, more particularly, in connection with molding machines of the type employing a turn-over pattern and flask-carrier, which latter is adapted, when in one position, to support the flask and pattern during the ramming operation, and when 20 turned over to the other position operates to invert the flask and deliver it to a support preparatory to the pattern-drawing operation.

My object, generally stated, is to provide 25 a novel and simple flask-receiving and supporting device which, when the flask is moved into engagement therewith, shall operate automatically to adjust itself to the flask employed, and which may be readily and quickly secured in automatically adjusted position for insuring the continuance 30 of the correct relative positions of the flask and flask-carrier during the drawing of the pattern and be released from such position, 35 as desired.

Referring to the accompanying drawings Figure 1 is a view in side elevation, partly 40 sectional, of a molding machine constructed in accordance with my invention. Fig. 2 is a section taken at the line 2 on Fig. 5 and viewed in the direction of the arrow, this view showing the machine in the position it assumes during the pattern-drawing operation. Fig. 3 is a detail of the flask-clamp 45 employed with its intermediate cross-brace and threaded rod therein omitted. Fig. 4 is a section taken at the line 4 on Fig. 3 and viewed in the direction of the arrow. Fig. 5 is an end view of the machine. Fig. 6 is an 50 enlarged section taken at the line 6 on Fig. 5 and viewed in the direction of the arrow; and Fig. 7, a section taken at the line 7 on Fig. 6, and viewed in the direction of the arrow.

55 The machine in connection with which I have chosen to illustrate my present inven-

tion is of the type illustrated and described in my said pending application and consists generally of a pattern and flask carrier journaled on the machine to be swung through approximately an arc of 180°, the carrier, when in one position, being adapted to receive a flask which, in practice, would be set over the pattern, and while in such position be rammed to form the mold and the carrier-flask and bottom board thereupon secured together, and when rocked from said position to its other position, to invert the flask and deliver it to a flask-support, whereupon the pattern is lifted bodily out of the mold.

The frame of the machine illustrated, which forms the support for the operating parts thereof as hereinafter described, is represented at 10 and is shown as supported 75 on three wheels 11 and 12 for facilitating the shifting of the machine from one place to another, the wheels 11 being located at one end of the frame and the wheel 12 at the other end thereof. The frame 10, at its 80 opposite sides and intermediate the wheels 11 and 12, is provided with a pair of vertically-disposed guide-posts 13 containing vertical, preferably lined, bores 14, which form guides for reciprocable rods 15 slidably confined in said bores. The upper ends of the rods 15 are provided with enlarged heads 16 which serve as stops for limiting the downward movement of the rods in the posts 13, these heads being connected together by a 90 shaft 17 journaled therein at its opposite ends. Rigidly connected with the shaft 17 is a pattern and flask-carrier 18 formed of a table-section 19, which, in the position of the machine represented in Fig. 1, rests 95 against a stop 20 on the frame 10, and arms 21 rigid with the section 19 and extending upwardly from a side of the latter and rigidly connected at their upper ends with the shaft 17, whereby the carrier 18 is marginally hinged to the upper ends of the rods 15 to permit the carrier to be swung upon these rods for the purpose hereinafter described. The heads 16 are provided on their inner sides with stub-shafts 22 upon which 100 depending links 23 are pivoted at their upper ends, the lower ends of these links being provided with laterally-projecting stub-shafts 24 at which these links are pivotally connected with the forward ends of spaced 110 levers 25 rigid with a sleeve 26 journaled on a shaft 27 fixed in opposite sides of the

frame. The stub-shafts 24 extend beyond the levers 25 and form pivotal connections for the lower ends of coiled springs 28, the upper ends of these springs being secured to lugs 29 rigid with the arms 21 of the carrier 18, but preferably diametrically opposed thereto, the springs 28 being so tensioned that when the carrier 18 is in the position represented in Fig. 1, they will be under sufficient tension to substantially counterbalance the carrier when loaded, whereby the loaded carrier may be readily swung by hand to inverted condition, for the purpose hereinafter described.

15 The normal position of the carrier 18 is that illustrated in Fig. 1, namely that in which its table-section 19 rests against the stop 20 on the frame, and the pattern, such as that represented at 30 and connected with 20 the carrier, is in inverted condition. The pattern 30 is preferably secured to boards 31 and the latter to the section 19 of the carrier to hold these parts rigid, as by means of screws 31^a. To make a mold from the pattern 30, a flask such as that represented at 25 32 is placed over the pattern and seated against the uppermost board 31. The molding sand is then rammed into the flask according to the usual practice of making 30 molds, and the bottom board 33 is then placed over the upper end of the flask.

After preparing the mold as described, the flask 32 and bottom board 33 are rigidly clamped to the carrier 18 in the positions 35 illustrated in Fig. 2, by means of clamping mechanism, a description of the preferred embodiment of which is as follows: The clamp-proper, which is represented at 34, is formed of a pair of spaced rods 35 of U- 40 shape, which are braced as indicated at 36 and 37, the brace 37 containing a threaded opening 38 in which an adjusting screw 39 operates. The rods 35 at one end are connected together by an integral loop-section 45 35^a, and at their opposite ends each is provided with a head 40 formed into the hook 41 and equipped with a guide-lug 41^a. The clamp 34 releasably engages at its hooks 41 with the shaft 17 and extends across the 50 upper end of the flask, the head 42 on the clamping-screw 39 bearing against the top surface of the bottom board 33 as represented in Fig. 1. The clamp 34 is releasably held in position for clamping the flask 32 and bottom board 33 to the carrier 18 through the medium of a link 43 which is bifurcated at its upper end to present arms 44 and is pivoted at its lower end to the carrier 18 beyond the flask as indicated at 45, 55 the link 43 being adapted to interlock at the offset portions 46 of the arms 44 with the section 35^a of the clamp 34. In order that the clamp 34 may be releasably interlocked with the link 43 as stated and released therefrom as desired, I provide a lever 47 which is

located between the offset portions 46 of the arms 44 and is pivoted on a shaft 48 secured in these arms. The lever 47 is provided with lugs 49 and 50 which extend beyond its pivotal connection with the link 43 and through the medium of which lugs the lever 47 serves to either spring the strap-section 35^a of the clamp 34 into interlocking engagement with the offset portions 46 of the arms 44 or disengage it therefrom depending upon the direction in which the lever 47 is operated, the under surfaces of the offset portions 46 of the arms 44 being preferably slightly concaved, as represented at 51, in order that the clamp 34 may be held in interlocking engagement with the link 43 against accidental release. In the preferred construction illustrated, the lever 47 merely operates to either spring the strap-section 35^a into interlocking engagement with the link 43, or disengage it therefrom, and does not assist in the holding operation. The screw 39 should be so adjusted in the brace 37 that when the clamp 34 is interlocked with the link 43 as stated, the rods 35 will be placed under relatively great tension for holding the bottom board 33 rigid on the flask 32 and the latter against shifting relative to the board 31 and pattern 30.

After the flask and the bottom board have been clamped to the carrier 18 as stated, the operator swings the loaded carrier to the right in Fig. 1 through one-half of a revolution to a position in which lugs 52 on the carrier 18 abut against stop-lugs 52 carried by the heads 16, the stops 53 serving to support the carrier 18 and the parts carried thereby.

In swinging the carrier at its hinge-connection with the rods 15 as stated, the pattern 30 and flask 32 are moved from inverted to upright condition, and the latter is delivered to flask-supports 54, constructed in accordance with my invention, for sustaining the flask during the pattern-drawing operation, a description of the preferred form in which said flask-supports are provided being as follows: Screwing into the frame 10 at its opposite sides are screw-standards 55 which are rendered adjustable up and down by reason of their threaded engagement with the frame 10, lock-nuts 56 screwing upon these standards serving to maintain the latter in adjusted position. Each of the standards 55 carries, at its upper end, a flask-supporting device 57, each of said devices being formed of a casing 58 open at opposite ends thereof and into socket 59 in the lower ends of which the upper ends of the respective standards 55 extend, the casings 58 being rigidly connected with these standards as through the medium of pins 60. Pivoted on shafts 61 fixed in opposite sides of each casing 58 and adjacent to its opposite ends are rock-levers 62, the outer 130

ends 63 of which, under the action of leaf-springs 64 partially surrounding bosses 65 on the levers 62 and engaging at their free ends with the under sides of the tops of the casings 58 and with pins 66 on the inner ends of these levers, normally extend in the upwardly-inclined position represented in Fig. 1, in which they project above the casings 58. The inner ends of the levers 62 are of segmental form, and co-operating with the arc-shaped surfaces 67 thereof are shoes 68 which are pivoted at their lower ends on bolts 69 secured in opposed walls of the casings, these shoes presenting arc-shaped surfaces 70 extending adjacent to the surfaces 67 of the levers 62. Pivoted on pins 71 fixed in the walls of extensions 72 of the casings 58 are rock-members 73 which extend transversely of the adjacent shoes 68 and the opposed side-walls of which converge upwardly as represented at 74, whereby the members 73 are rendered wedge-shape in cross-section, the portions of the shoes 68 adjacent to the members 73 being provided with lugs 75 presenting upwardly-converging surfaces 76 which oppose the surfaces 74 on the members 73, whereby when the latter are rocked upwardly on their pivots 71, as hereinafter described, they will force the respective shoes 68 into rigid clamping engagement with the levers 62 and hold the latter against turning on their pivots 61. The levers 77, which are pivoted on the casings 58 as indicated at 78 and are pivotally connected, as indicated at 79, beyond the pivots 78 to upwardly-extending links 80 having pivotal connection at their upper ends with the outer ends of the members 73 as indicated at 81, operate as the medium through which the rock-members 73 are operated for the purpose stated.

As the carrier 18 nears the limit of its turning movement, as hereinbefore described, the bottom board 33 engages with the upper ends 63 of the levers 62, and in coming to rest against the stops 53 swings the levers 62 downwardly against the action of the springs 64 to a point at which these levers become automatically adjusted to the position assumed by the bottom board 33. The operator thereupon swings the levers 77 downwardly, thereby swinging the members 73 upwardly and by reason of the wedging action produced against the shoes 68, forcing the latter into clamping engagement with the levers 62, thus locking the latter in rigid condition for securely supporting the flask 32 when the latter is released from the carrier as hereinafter set forth. After the levers 62 have been set in the positions automatically assumed by them as stated, the operator releases the clamp 34 from engagement with the link 43 by swinging the operating lever 47 to a position in which the lug 50 engages with the

strap-section 35^a of the clamp and springs it out of interlocking engagement with the offset portions of the arms 44. The clamp 34 thus released, swings at its hook-portions 41 upon the shaft 17, its brace-bar 36 automatically entering the space between the upper and lower arms 82 and 83 respectively of a fork-member 84 secured to the frame 10, and its opposite free end resting on the frame as indicated in Fig. 2, the hook-portions 41 of the clamp 34, when the latter assumes the position just stated, being withdrawn to a position in which they extend out of the path of upward movement of the shaft 17 as represented in Fig. 2, whereby the shaft 17 and the parts carried thereby may be raised for the purpose hereinafter described, without disturbing the position assumed by the clamp-bar 34 as represented in the last referred to figure. The lugs 41^a by extending in the rear of the shaft 17, operate, upon the release of the clamp 34, as stated, to insure the positioning of the latter as explained. The flask having been thus transferred from the carrier 18 to the flask-supports 54, the next operation is that of withdrawing the pattern 30 from the mold, and this is accomplished by bodily raising the rods 15, and all of the parts carried thereby, through the medium of a foot-lever 85 which is rigidly connected with the sleeve 26 and when depressed operates to swing the levers 25 upwardly, and through the medium of the links 23, elevate the rods 15, springs 28 and carrier 18 to a position in which the pattern 30 is drawn from the mold as represented in Fig. 2, the rods 15 in this operation moving in the posts 13 for guidance. To minimize the power required for elevating the carrier 18 as described, I provide a coiled spring 86 which is secured at one end to the frame of the machine and at its opposite end to a depending lug 87 on the sleeve 26. It will be noted that in the pattern-drawing operation described, the pattern is moved in a path at a right-angle to the mold which insures the pattern being withdrawn from the latter without impairing the mold. The springs 28 are preferably so tensioned that they tend to swing the carrier 18 and the pattern 30 to raised position when the mold is released therefrom as described, in which case the operator bears down on the carrier for maintaining the lugs 52 in engagement with the stops 53 during the operation of bodily raising the carrier and its supports as hereinbefore described. Thus, as soon as the rods 15 have been raised sufficiently far to draw the pattern from the mold, the operator releases his grasp on the carrier and permits the latter to swing upwardly. The operator thereupon removes the pressure from the foot-lever 85, permitting the rods 15 and the parts carried there-

by to descend. The mold is then removed from the flask-supports 54 and the carrier 18 swung back to the normal position represented in Fig. 1 for receiving another flask. 5 the shaft 17 in the lowering movement of the rods 15 as described, descending to a position in which it opposes the hooks 41. The clamp 34 after the newly positioned flask has been filled and the bottom board 10 applied thereto, is moved from the position illustrated in Fig. 2 to clamping position, by the operator grasping the free end of the clamp and lifting it, thereby causing the hooks to be automatically projected over the 15 shaft 17 and swinging upon this shaft as a pivot. It will be understood that preparatory to each operation of delivering a filled flask to the flask-supports 54 as described, the rock-levers 62 are released to permit 20 them to assume normal condition, namely that illustrated in Fig. 1, by operating the levers 77 reversely to that hereinbefore described.

In order to avoid any danger of impairment to the machine should the carrier 18 be swung over the center of its axis when moved from the position in which it extends over the supports 54, I provide stops 88 on the carrier which coöperate with the heads 16 and limit the movement of the carrier. Through the medium of the screw-standards 55 the supports 54 may be raised or lowered as desired to adjust the machine for use with flasks of varying heights.

35 It will be observed that in the construction illustrated two of the flask-engaging fingers 62 are provided at each side of the machine, thus affording a support for the flask at four different points, and that only
40 two levers are required to be operated for setting and releasing the four fingers 62, this feature of my machine being of importance as but one-half the time is required in my construction for setting and releasing
45 the flask-supporting fingers as compared with the time required for operating the devices employed for this purpose in prior constructions.

In carrying out my invention I prefer to provide springs, as described, for co-operation with the levers 62 to hold them yieldingly in raised condition under spring tension, but it will be manifest to those skilled in the art that in the illustrated embodiment of my invention these springs may be omitted, if desired, and the unbalanced weight of the levers 62 tending to move them to a position in which an end of each thereof is raised, be relied upon to hold said levers yieldingly in raised condition.

The features herein shown and not claimed are included in my application Serial No. 631,292, filed June 5, 1911, patented May 21, 1912, No. 1,027,066.

65 While I have illustrated and described the

form of flask-receiving and supporting device which I now consider to be the preferred form in which my invention may be embodied, and a modification thereof, I do not wish to be understood as intending to limit my invention to such forms, as various changes and alterations may be made therein without departing from the spirit of my invention. Furthermore, by illustrating and describing my improved flask-receiving and supporting device in connection with a particular type of turn-over pattern and flask carrier, I do not wish to be understood as intending to limit it to its use in this connection, it being my desire to claim it for use in any situation in which it may have utility. 70 75 80

What I claim as new, and desire to secure by Letters Patent, is—

1. In a flask-receiving and supporting device, the combination of a base, a plurality of independently adjustable flask-engaging members fulcrumed thereon to rock up and down and each adapted to contact at one end only with a flask seating thereon, and means for holding said members in independently adjusted positions. 85 90

2. Flask-receiving and supporting means comprising in combination a base, a plurality of flask-engaging members fulcrumed thereon to rock up and down and each adapted to contact at one end only with a flask resting thereon, and means for yieldingly holding said members in raised position. 95

3. Flask-receiving and supporting means comprising in combination a base, a plurality of flask-engaging members fulcrumed thereon to rock up and down and each adapted to contact at one end only with a flask resting thereon, and springs for yieldingly holding said members in raised position. 100 105

4. Flask-receiving and supporting means comprising, in combination, a base, a plurality of yieldable flask-engaging members fulcrumed thereon to rock up and down, and means for releasably securing said members in the positions to which they are automatically moved when engaged by the flask. 115

5. In a flask-receiving and supporting device, the combination of a base, a plurality of independently adjustable flask-engaging members fulcrumed thereon to rock up and down and each adapted to contact at one end only with a flask seating thereon, and means for lifting the flask-engaging ends of said members and yieldingly holding them in raised condition 120

6. In a flask-receiving and supporting device, the combination of a base, a plurality of independently adjustable flask-engaging members fulcrumed thereon to rock up and down and each adapted to contact at one end only with a flask seating thereon, and 130

springs for raising the flask-engaging ends of said members and yieldingly holding them in raised condition.

7. In a flask-receiving and supporting device, the combination of a base, a plurality of independently adjustable flask-engaging members fulcrumed thereon to rock up and down and each adapted to contact at one end only with a flask seating thereon, means for lifting the flask-engaging ends of said members and yieldingly holding them in raised condition, and means for securing said members in the positions to which they are moved when engaged by the flask.

15. 8. In a flask-receiving and supporting device, the combination of a base, a plurality of independently adjustable flask-engaging members fulcrumed thereon to rock up and down and each adapted to contact at one end only with a flask seating thereon, springs for raising the flask-engaging ends of said members and yieldingly holding them in raised condition, and means for securing said members in the positions to which they are moved when engaged by the flask.

25. 9. Flask-receiving and supporting means comprising, in combination, a base, a plurality of flask-engaging members fulcrumed thereon to rock up and down, means for yieldingly holding said members in raised position, and means for releasably securing said members in the positions to which they are automatically moved when engaged by the flask.

35. 10. Flask-receiving and supporting means comprising, in combination, a base, a plurality of flask-engaging members fulcrumed thereon to rock up and down, means for yieldingly holding said members in raised position, and means for releasably securing said members in the positions to which they are automatically moved when engaged by the flask.

45. 11. Flask-receiving and supporting means comprising, in combination, a base, a plurality of flask-engaging members fulcrumed on said base to rock up and down thereon, means tending to yieldingly hold said members in raised position, and brake mechanism for releasably securing said members in the positions to which they are moved when engaged by the flask.

55. 12. Flask-receiving and supporting means comprising, in combination, a base, a plurality of flask-engaging members fulcrumed on said base to rock up and down thereon, means tending to yieldingly hold said members in raised position, and brake mechanism for releasably securing said members in the positions to which they are moved when engaged by the flask.

65. 13. In a molding-machine, flask-receiving and supporting means comprising, in combination, a plurality of pivotally supported flask-receiving and supporting members,

means for yieldingly holding said members in raised position, pivotally supported brake-levers coöperating with said members, and a rock-member for operating said brake-levers, for the purpose set forth.

70. 14. In a molding-machine, flask-receiving and supporting means comprising, in combination, pivotally supported flask-receiving and supporting members, means for yieldingly holding said members in raised position, pivotally-supported brake-levers coöperating with said members, and wedging mechanism for operating said brake-levers, for the purpose set forth.

75. 15. Flask-receiving and supporting means comprising, in combination, a base, pairs of flask-engaging members fulcrumed on said base to rock up and down thereon and normally extending in raised position, and a single device for each pair of said members for releasably securing the latter in the positions to which they are moved when engaged by the flask.

80. 16. Flask-receiving and supporting means comprising, in combination, a base, pairs of flask-engaging members fulcrumed on said base to rock up and down thereon, means for yieldingly holding said members in raised position, and a single device for each pair of said members for releasably securing the latter in the positions to which they are moved when engaged by the flask.

85. 17. Flask-receiving and supporting means comprising, in combination, a base, pairs of flask-engaging members fulcrumed on said base to rock up and down thereon and normally extending in raised position, and a single device operating by frictional contact with said members to releasably hold the latter in the positions to which they are moved when engaged by the flask.

90. 18. In a flask-receiving and supporting device, the combination of a base, pairs of independently adjustable flask-engaging members fulcrumed on said base to rock up 110 and down thereon and each adapted to contact at one end only with the flask, and a single device for each pair of said members for releasably securing the latter in independently adjusted positions.

115. 19. In a molding-machine, flask-receiving and supporting means comprising, in combination, pairs of pivotally supported flask-receiving and supporting members, means for yieldingly holding said members in 120 raised position, pivotally-supported brake-levers located adjacent to said members, and means coöperating with each pair of brake-levers for operating the latter, for releasably securing said members in automatically 125 adjusted position, for the purpose set forth.

20. In a molding-machine, flask-receiving and supporting means comprising, in combination, flask-receiving and supporting members pivotally supported between their ends, 130

with their lower ends of curved shape, means 5 for releasably holding their upper ends in raised position, brake-levers pivotally supported on the machine and having curved surfaces coöperating with the curved surfaces of said members, and means for operating said levers, for the purpose set forth.

21. In a molding-machine, flask-receiving and supporting means comprising, in combination, flask-receiving and supporting members pivotally supported between their ends, means for yieldingly holding said members at their upper ends in raised position, brake-levers pivoted on the machine adjacent to the lower ends of said members, wedging-members pivotally connected with the machine and located between pairs of said brake-levers, and means for actuating said wedging-members, for the purpose set forth.

22. In a molding-machine, flask-receiving and supporting means comprising a plurality of members pivotally supported in unbalanced condition and means for releasably securing said members in the positions to which they are automatically moved when engaged by the flask, for the purpose set forth.

23. In a molding-machine, flask-receiving and supporting means comprising a plurality of members pivotally supported in unbalanced condition and brake-mechanism for releasably securing said members in the positions to which they are moved when engaged by the flask.

24. Flask-receiving and supporting means comprising in combination, a plurality of yieldable pivotally supported flask-receiving and supporting members, pivotally supported brake-levers coöperating with said members, and a rock member for operating said brake-levers, for the purpose set forth.

25. Flask-receiving and supporting means comprising in combination, pivotally supported yieldable flask-receiving and supporting members, pivotally supported 45 brake-levers coöperating with said members, and wedging mechanism for operating said brake-levers, for the purpose set forth.

EDWARD A. PRIDMORE.
